Application February 21, 1947, Serial No. 729,966

7 Claims. (Cl. 291—16)

1

The invention relates to track sanders for locomotives, and more particularly to the engineer's valve for controlling the delivery of the sand by compressed air, from the usual sand traps.

Heretofore, it has been common practice to employ valve-mechanism which includes a rotatable disk or element which is provided with a through-port and adapted to be set into positions for controlling respectively, the delivery of air to one or more traps for clean-out blasts, and to sand delivery nozzles in the traps. In this mechanism, one face of the rotatable disk fitted against a seat in the casing which was provided with conduits communicatively connected to the sand traps respectively. In practice, it has been found that leakage is sometimes caused by imperfectly fitting casing sections or engaging faces of the disk and its seat, or particles becoming lodged between said faces, or from other causes, so that when the disk was set to cut off the supply of compressed air to the sand trap, a considerable volume of compressed air was wasted. In the operation of track sanders by compressed air, a desideratum is to conserve the air supply.

The main object of the present invention, is to provide valve mechanism of this type which includes an auxiliary valve controlled by the rotative movements of the valve disk for automatically cutting off the supply of compressed air to the valve-disk chamber in the casing, to eliminate unilateral pressure and drag on the valve-disk for ease of its operation, preventing leakage of air from the casing while the valve-disk is set to cut off delivery of air to the trap and to prevent the delivery of air to the clean-out blast during the return of the valve-disk to its neutral position after each sanding operation.

Another object of the invention is to provide a valve of this type in which the auxiliary valve is controlled to prevent the delivery of air to the clean-out duct of the trap, during the return stroke of the disk to its neutral position, by simple cam means on the valve-disk.

Other objects of the invention will appear from the detailed description.

The invention consists of the several novel features hereinafter set forth and more particularly defined by claims at the conclusion hereof.

In the drawings:

Fig. 1 is a front elevation of a valve embodying the invention.

Fig. 2 is a section taken on line 2—2 of Fig. 1.

Fig. 3 is a section taken on line 3—3 of Fig. 2.

Fig. 4 is a partial section similar to Fig. 2, illustrating the valve disk rotated to open the

2

auxiliary valve for the flow of compressed air to the valve chamber.

Fig. 5 is a similar section illustrating the lever for opening the auxiliary valve while it is being shifted radially by the cam means on the valve-disk, so the auxiliary valve will remain closed to prevent the delivery of air to the clean-out duct during the return stroke of the valve-disk to its normal position after a sanding operation has been completed.

Fig. 6 is a face view of the casing section which contains the valve-disk with the lever for controlling the auxiliary valve.

Fig. 7 is a face view of the valve-disk.

Fig. 8 is a perspective of the cam-means on the valve-disk.

Fig. 9 is a face view of the valve-disk, illustrating the movement of the lever for controlling the auxiliary valve during a return stroke of said disk.

The invention is exemplified in valve-mechanism which comprises a casing formed of outlet and inlet sections 10 and 11, which are secured together by screws 12. A pipe 13 leading from a source of compressed air supply, is connected to the section 11 of the casing. Pipes 14 and 15 are connected to receive air from separate conduits in the casing-section 10, and are connected respectively to the ducts in a pair of sand traps, for delivering clean-out blasts to the sand traps, as well understood in the art. Pipes 16 and 17 are connected to receive air from separate conduits in casing-section 10, and are connected respectively to deliver air for discharging sand from a pair of traps, as well understood in the art. A chamber 18, in the casing, is adapted to receive air from supply pipe 13, under control of the auxiliary valve hereinafter described. A valve-disk 19 is rotatable in the chamber 18, and has one of its faces fitting against the face 20 in valve section 10, which forms a seat for said disk. Disk 19 is rotatable by a stud 21, which is connected to the disk by a rib 22. Stud 21 has affixed thereto, a handle or lever 23, which is provided

45 with a spring-pressed dog 24, which is adapted to engage a series of notches 26, formed in a segment on the casing-section 10, for yieldably holding the lever in its different selective and predetermined positions. A port 27 extends through 50 valve-disk 19, and controls the flow of air from chamber 18, to a pair of ducts 28, 29, in casing-section 10, which are communicatively connected to pipes 14 and 15 respectively, and to ducts 30—31, which are communicatively connected to pipes 16 and 17 respectively. In practice, pipes

14 and 16 are connected to the clean-out duct and to the nozzle for delivering sand respectively, from one trap to sand the rails when the locomotive is travelling forwardly, and pipes 15 and 17 are connected respectively to the clean-out duct and to the sand delivery nozzle of a second trap to sand the rails when the locomotive is travelling in the reverse direction. By rotation of the handle 23, disk 19 may be rotated to selectively supply air separately to the ducts 28, 29, 30 and 31, for controlling the delivery of air through pipes 14 and 15, to the clean-out ducts of the sand traps and through pipes 16 and 17, to control the flow of air to the nozzles of sand traps for discharging sand onto the rails.

An auxiliary valve, generally designated 33, is mounted in the inlet casing-section 11, and controls the flow of air from a chamber 34, which is communicatively connected to the air supply pipe 13, through a passage 35, into the chamber 18. Valve 33 comprises a stem 36, which is slidably mounted in a cap 37, a packing 38 secured on a head 39 by a screw 40, and a washer 40^a. A spring 42 is adapted to normally close the exposed face of the packing disk 38, against a seat 41, which surrounds the opening 35. The auxiliary valve 33 is controlled by cam means generally designated 46, which is integral with and projects from, one face of the valve-disk 19 adjacent its outer periphery, and a lever 43, which is shiftable by said cam means.

The lever 43 has its upper end adapted to fulcrum on the face 20 of disk 19, has a V-shaped corner 45 at its lower end which engages cam-means 46, and is provided with an extension or abutment 47 which is adapted to engage a part of valve 33, such as screw 40, to open said valve by forcing it away from its seat 40 against the force of spring 42. Lever 43 is confined in a recess 44 in casing section 11, for pivotal movement and for sliding movement. A spring 48 in casing-section 11, urges lever 43 toward the face 20^a of disk 19 and permits pivotal or angular movement of said lever. A spring 60, confined in the upper end of lever 43, urges the lever downwardly against the periphery of chamber 18 and permits vertical sliding movement of the lever.

Cam means 46 includes two sets of members, each set of which, as the valve-disk 19 is shifted in one direction from its neutral position, will control successively, the operation of the lever 43 to open auxiliary valve 33 for a clean-out blast; close said valve after a clean-out blast; and reopen the auxiliary valve, for air to the sand delivery nozzle of one trap, under control of the port 27 in disk-valve 19. One set of cam-members controls lever 43 for the operation of one trap when valve-disk 19 and handle 23 are shifted in one direction, and the other set similarly controls lever 43 for the operation of the second sand trap when handle 23 and disk 19 are rotated in the opposite direction. Each set of cam-members includes an outwardly inclined or rising face 51, for shifting lever 43 to open valve 33 for a clean-out blast; an inwardly inclined face 52, for closing the auxiliary valve after a clean-out blast; an outwardly inclined face 53, for opening valve 33 for air to the sand delivery nozzle; and a flat face 54, for holding valve 33 open to continue the sanding operation until it has been completed. The portion of each cam-member on which the inwardly inclined face 52 is formed, is beveled at 55 from a point at its inner end to the full width at the outer end of said face, for radially shifting lever 43 to prevent it from opening valve

33 during the return stroke of handle 23 and disk 19, from sanding to neutral position.

The operation of the valve will be as follows: While handle 23 is in its neutral or central position, port 27 will be out of communication with the ducts 28, 29, 30 and 31, which lead to the pipes 14, 15, 16, 17, respectively. Valve 33 will then be closed against its seat 40, spring 42 will hold lever 43 against disk 19, and no compressed air will be supplied to chamber 18. The pressure of spring 48 applied to lever 43, will hold it in engagement with the face 20^a of the disk 19 and the corner 45 of said lever will be positioned between the cam faces 51. Valve 33 will be closed, so that no air can pass into chamber 18 or leak around valve-disk 19. For a sanding operation, handle 23 will be shifted from its normal position, illustrated in Fig. 1, forwardly or rearwardly, according to the sand trap to be operated. When handle 23 is shifted in one direction from its neutral position, disk 19 will be rotated therewith to bring its port 27 successively into registry with a duct 28 for a clean-out blast and a duct 30 for air to the sand discharge nozzle of the trap to which said ducts are connected. Assuming the handle to be shifted in clockwise direction, a cam face 51 will engage the lower end of and angularly shift, lever 43, so its abutment 47 will open valve 33 and admit air to chamber 18 from which it passes through port 27 into duct 28 for delivering a clean-out blast through pipe 14 to the clean-out duct in said sand trap. During the continued rotation of handle 23 and disk 19 in the same direction, lever 43 will ride on a cam face 52 and the lever will move angularly, to permit valve 33 to close and cut off the supply of air to chamber 18. Next, a cam face 53 will shift lever 43 angularly, to again open valve 33 until the lever engages the flat face 54. At this time, port 27 in disk 19 will register with duct 30 and air will be delivered through pipe 16 to the sand delivery nozzle in said trap. When the sanding operation is to be stopped, the engineer will return lever 23 to its neutral position. During this shift, cam face 53 will allow lever 43 to swing angularly for closing valve 33 during the initial portion of the return stroke of disk 19. During continuing rotation of disk 19 and handle 23, beveled cam-face 55 will engage the lower end 50 of lever 43 and shift the lever radially, as illustrated in Fig. 5, against the force of spring 60, without imparting angular movement to the lever, so that during the return stroke of handle 23 and disk 19, valve 33 will remain closed and 55 no air will be delivered to chamber 18 or duct 28, to prevent a clean-out blast during the return stroke of the disk. After being lifted by bevelled cam face 55, lever 43 will ride on the face 58, until disk 19 is in its neutral position. Then lever 60 43 will be shifted downwardly by spring 60, to its normal position against the inner periphery of chamber 18. The valve will then be in its neutral position, in readiness for a succeeding sanding operation. When the other sand trap 65 to which pipes 15 and 17 are connected, is to be operated, handle 23 will be shifted rearwardly or in reverse direction, for successively delivering a clean-out blast to the sand delivery nozzle in the same manner as before described. The other set of cam-members will then control the air to chamber 18 in the same manner described. During the return stroke of handle 23 and disk 19, lever 43 will be shifted by a bevelled cam-face 55, against the force of spring 60 to keep valve 33 closed, as before described.

The invention exemplifies controlling mechanism for a sand trap which comprises a rotatable valve-disk with a port therein, for controlling the delivery of air to the clean-out ducts and the sand delivery nozzles of sand traps, and an automatically closing auxiliary valve controlled by the disk, for cutting off the supply of air from the supply pipe to the disk chamber, so that there will be no leakage of air from the casing around the valve-disk when the sanding mechanism is not in operation, and means for cutting off air during substantially the entire return stroke of the valve-disk.

The invention is not to be understood as limited to the details described, since these may be modified within the scope of the appended claims without departing from the spirit or scope of the invention.

Having thus described the invention, what I claim as new and desire to secure by Letters Patent is:

1. In controlling mechanism for a sand trap provided with an air nozzle for discharging sand and a duct for a clean-out blast, the combination of a casing provided with conduits for separately delivering air to the nozzle and the clean-out duct, a valve element rotatable in the casing, provided with a port for successively controlling delivery of air to said conduits, and with rotatable cam means, a normally closed auxiliary valve in the casing for controlling the supply of compressed air to said element, and means for opening the auxiliary valve movable in the casing, said cam means including faces for shifting said opening-means to open the auxiliary valve for the successive delivery of air to the nozzle and the clean-out duct when the disk is rotated in one direction and a face for shifting said means to leave the auxiliary valve closed during the return stroke of said element to its normal position.

2. In controlling mechanism for a sand trap provided with an air nozzle for discharging sand and a duct for a clean-out blast, the combination of a casing provided with conduits for separately delivering air to the nozzle and the clean-out duct, a valve element rotatable in the casing, provided with a port for successively controlling delivery of air to said conduits, and with rotatable cam means, a normally closed auxiliary valve in the casing for controlling the supply of compressed air to said element, and a lever for opening the auxiliary valve movable in the casing, said cam means including faces for shifting said lever to open the auxiliary valve for the successive delivery of air to the nozzle and the clean-out duct when the disk is rotated in one direction and a face for shifting said lever to leave the auxiliary valve closed during the return stroke of said element to its normal position.

3. In controlling mechanism for a sand trap provided with an air nozzle for discharging sand and a duct for a clean-out blast, the combination of a casing provided with conduits for separately delivering air to the nozzle and the clean-out duct, a valve element rotatable in the casing, provided with a port for successively controlling delivery of air to said conduits, and with rotatable cam means, a normally closed auxiliary valve in the casing for controlling the supply of compressed air to said element, and means for opening the auxiliary valve movable angularly and slidably in the casing, said cam means including faces for angularly shifting said means to open the auxiliary valve for the successive delivery

of air to the nozzle and the clean-out duct when the disk is rotated in one direction and a face for slidably shifting said means to leave the auxiliary valve closed during the return stroke of said element to its normal position.

4. In controlling mechanism for a sand trap provided with an air nozzle for discharging sand and a duct for a clean-out blast, the combination of a casing provided with conduits for separately delivering air to the nozzle and the clean-out duct, a valve element rotatable in the casing, provided with a port for successively controlling delivery of air to said conduits, and with rotatable cam means, a normally closed auxiliary valve in the casing for controlling the supply of compressed air to said element, and a lever for opening the auxiliary valve movable angularly and slidably in the casing, said cam means including faces for angularly shifting said lever to open the auxiliary valve for the successive delivery of air to the nozzle and the clean-out duct when the disk is rotated in one direction and a face for slidably shifting said lever to leave the auxiliary valve closed during the return stroke of said element to its normal position.

5. In controlling mechanism for a plurality of sand traps, each provided with an air nozzle for discharging sand and a duct for a clean-out blast, the combination of a casing provided with conduits for separately delivering air to the nozzle and the clean-out duct of each trap, a rotatable valve disk in the casing provided with a port for successively controlling the delivery of air to each trap and with cam means, a normally closed auxiliary valve in the casing for controlling the supply of compressed air to the valve disk, and means for opening the auxiliary valve, said cam means including faces for angularly shifting said means to open the auxiliary valve for successive air to the ducts in the casing for the air nozzle and the clean-out duct in the traps, respectively, when the disk is rotated in opposite directions, and faces for shifting said means to leave the auxiliary valve closed during the return strokes of the disk to its neutral position.

6. In controlling mechanism for a plurality of said traps, each provided with an air nozzle for discharging sand and a duct for a clean-out blast, the combination of a casing provided with conduits for separately delivering air to the nozzle and the clean-out duct of each trap, a rotatable valve disk in the casing provided with a port for successively controlling the delivery of air to each trap and with cam means, a normally closed auxiliary valve in the casing for controlling the supply of compressed air to the valve disk, and a lever for shifting the auxiliary valve, said cam means including faces for angularly shifting said lever to open the auxiliary valve for successive air to the ducts in the casing for the air nozzle and the clean-out duct in the traps, respectively, when the disk is rotated in opposite directions, and faces for shifting the lever to leave the auxiliary valve closed during the return strokes of the disk to its neutral position.

7. In controlling mechanism for a plurality of sand traps, each provided with an air nozzle for discharging sand and a duct for a clean-out blast, the combination of a casing provided with conduits for separately delivering air to the nozzle and the clean-out duct of each trap, a rotatable valve disk in the casing provided with a port for successively controlling the delivery of air to each trap and with cam means, a normally closed aux-

iliary valve in the casing for controlling the supply of compressed air to the valve disk, and a lever for shifting the auxiliary valve angularly movable and slideable in the casing, said cam means including faces for angularly shifting the lever to open the auxiliary valve for successive air to the ducts in the casing for the air nozzle and the clean-out duct in the traps, respectively, when the disk is

rotated in opposite directions, and faces for slideably shifting the lever to leave the auxiliary valve closed during the return stroke of the disk to its neutral position.
